H. B. WEAVER.

Breech-Loading Fire-Arm.

No. 13,691.

Patented Oct. 16, 1855.

UNITED STATES PATENT OFFICE.

H. B. WEAVER, OF SOUTH WINDHAM, CONNECTICUT.

IMPROVEMENT IN BREECH-LOADING FIRE-ARMS.

Specification forming part of Letters Patent No. 13,691, dated October 16, 1855.

To all whom it may concern:

Be it known that I, H. B. WEAVER, of South Windham, in the county of Windham and State of Connecticut, have invented certain new and useful Improvements in Breech-Loading Fire-Arms; and I do hereby declare that the following is a full, clear, and exact description of the same, reference being had to the accompanying drawings, forming part of this specification, in which—

Figure 1 is a side view, partly in section, of the breech and lock of a gun constructed according to my invention. Fig. 2 is a transverse section of the same, taken close in rear of the priming-slide.

Similar letters of reference indicate corresponding parts in both figures.

This invention consists in certain contrivances for effecting the cocking of the hammer simultaneously with the opening of a laterally-swinging chamber, and for operating a priming-slide to supply percussion-caps or other priming from a magazine.

To enable those skilled in the art to make and use my invention, I will proceed to describe its construction and operation.

A is the chamber, which is formed in one piece with or attached permanently and solidly to the breech, and is hinged by a hinge, a, parallel with its bore to the break-off plate B, which connects the stock and barrel. The front and rear ends of the chamber are faced to form parallel planes perpendicular in all directions to its bore, and the chamber is fitted easily but closely in a parallel cavity formed between the rear of the barrel c and a shoulder, b, at the top of the break-off plate, its front end forming a close joint with the rear of the barrel, and its back end fitting close up to the shoulder b, which receives the recoil. The pivot of the hinge a, which has the chamber firmly attached to it, carries a short lever-arm, c, (shown best in Fig. 2,) which enters a slot in a sliding piece, d, which I call the "priming-slide," which serves both to prime and to effect the connection between the chamber and the front end of a trigger-guard lever, D, which works loosely on the main arbor e of the lock, and serves to effect all the necessary movements except that of the hammer for exploding the priming.

E is a tubular cavity, serving as a magazine

for caps, arranged parallel with the bore of the piece in the upper part of the stock or break-off. The priming-slide d, which works perpendicularly to the bore, is of a thickness equal to the depth of a cap, and has a receiving-hole in it just large enough to receive a cap, so that when it is raised by pulling down the rear end of the trigger-guard lever this receiving-hole is brought opposite the magazine, and a cap is forced into it by the spring g, at the back of the magazine, and when it is lowered by raising the trigger-guard lever the hole it is brought between the nipple j, which is on the breech, and a sliding pin, h, which stands in line with the nipple. The slide d is shown in Fig. 1 and in black outline in Fig. 2 in the last-described position, with a cap, i, between the nipple and pin, ready to be driven on the nipple and exploded by the hammer F, driving forward the pin h when it is liberated by drawing the trigger. The hammer is thrown back and cocked by pulling down the lever D by reason of its being provided with a stud, k, standing out from each side, to be in the way of the forward part of lever D as it rises; but as there is no absolute connection between the trigger-guard and the hammer, the lever is allowed to be returned to its position as a guard, leaving the hammer cocked.

The connection of the lever D with the priming-slide d is effected by means of a stud, l, on the lever working in a hole, n, in a link, o, attached to the bottom of the slide.

In order to allow the sliding pin h to move back, which it must do before the slide d can move upward, the hammer must be drawn back some distance before the lever, acts on the slide, and for this purpose the hole n, which receives the stud l, is elongated, as shown in Fig. 1, so that the lever, in drawing back the hammer, moves some distance independently of the slide. The pin is thrown back by a spring, m, coiled round it as the hammer recedes, and by the time the pin h is clear of the slide the stud l arrives at the top of the hole n, and the movement of the slide and the swinging aside of the chamber toward the position shown in red outline in Fig. 2, in which position it receives the charge, commence. The opening of the chamber and the cocking of the hammer are completed at the

same time, and as soon as the chamber is loaded the lever D may be raised to its position as a guard, (shown in Fig. 2,) leaving the hammer cocked. As the hammer and whole of the lock is shut up, I allow the arbor *e* to protrude through the covering-plate of the lock for the purpose of carrying a small thumb-lever, G, which is represented in dotted outline in Fig. 1, to enable the hammer to be uncocked and cocked by hand independently of the lever D, the chamber, or the priming-slide.

In constructing the lever D care should be taken to prevent the pin *h*, when the hammer strikes, from striking the said lever, and for that purpose it will be seen, by looking at the red outline of the hammer in Fig. 1, that I have left a little room in the bottom of the recess *p* in the lever which receives the pin.

Having thus fully described my invention, I will proceed to state what I claim and desire to secure by Letters Patent—

1. Though I do not claim the invention of the priming-slide *d*, I claim combining the hammer with the laterally-swinging chamber

for the purpose of effecting the simultaneous opening of the chamber and cocking of the hammer by means of the lever D, the pin *k*, the slide *d*, and lever-arm *c*, all operating substantially as herein described, whether the said slide *d* be a priming-slide or simply employed to connect the chamber A with the lever D.

2. Combining the priming-slide *d* with the lever D and the hammer F by means of a pin, *l*, attached to the lever working in a slot, *n*, in the slide, or a link attached thereto, so that the lever D will draw back the hammer before moving the slide far enough to allow the pin *h* or its equivalent, through which the hammer strikes the cap, to move out of the receiving-hole in the slide before the slide is acted upon by the lever, substantially as herein set forth.

H. B. WEAVER.
